UNITED STATES PATENT OFFICE.

DANIEL YOUNG, OF BROOKLYN, NEW YORK, ASSIGNOR TO YOUNG INVENTIONS, INC.,
A CORPORATION OF NEW YORK.

HOSIERY.

Application filed August 23, 1922. Serial No. 583,891.

To all whom it may concern:

Be it known that I, DANIEL YOUNG, a subject of the King of Great Britain, and resident of Brooklyn, in the county of Kings and 5 State of New York, have invented certain new and useful Improvements in Hosiery, of which the following is a specification.

This invention relates to improvements in hose or stockings such as are worn by men, 10 women and children, and is especially adapted for that style known as the half hose or stocking.

The objects of this invention are to provide a hose or stocking of this character 15 which will conveniently and easily adjust itself to the leg and which is comfortable to the wearer and does not unnecessarily bind or pinch the leg; but has a light and clinging effect thereto, without the use of an additional support such as is in use at the present time.

It will be seen I accomplish the foregoing by referring to the drawings forming a part 20 of this specification in which Fig. 1 is a vertical sectional view of the upper portion of my improved hose or stocking, and is shown as it is manufactured; Fig. 2 is a vertical sectional view of the hose or stocking shown in Fig. 1 with the top folded over, 25 and ready to be applied to the leg of the wearer; Fig. 3 is a horizontal sectional view taken on the line 1—1 of Fig. 2.

Referring to the drawings which show a general embodiment of this invention and it 30 being understood are more or less diagrammatic of a knitted hose, it will be seen there can be many changes in the general form of construction without departing from the spirit of my invention, and it will be understood that the principal point of this invention 35 is to provide a hose or stocking having a top so formed that it will cling to any part of the leg whether it is located above or below the knee, and does not depend on any subsidiary member to retain it in the 40 position in which it is placed, and the top being so retained that it will securely support the rest of the stocking, and cause it to snugly fit the leg of the wearer.

Referring to Figs. 1 to 3 it will be seen I 45 provide a hose or stocking 2 having a double top as shown at 3 and 4. The top 3 is different from the top 4, inasmuch as it is composed of more threads in its construction, 50 and the tension of the machine used in form-

ing the same is so arranged to make a tighter or closer construction and this causes the material to be thicker and stronger in the top 3 than it is in the top 4. In other words the top 3 when the stocking is made of a 60 coarse material may have three or four threads passing into the machine and introduced into the top 3, and when the top 4 and the rest of the stocking is being made only two threads will be passing into the 65 machine, and also the tension on the threads will be increased for the top 4, thus causing the diameter of the top 4 to be slightly less than the diameter of the top 3, so that when the top 3 is folded over the top 4 the two 70 tops will be in parallel plains with each other. It will be understood that while I have given for example the combination of the difference between the two tops, as regards to threads, as three to two or four to 75 two, I do not confine myself to this combination as the difference of material both as regards to quality and gauge and also kind of material used, will necessitate a great variety 80 of combinations as regards to the number of threads to be used in each top relative to the other. The invention lies in the fact that by using more threads in one top, which makes it stronger and less elastic than the other top, and also the rest of the stocking, it 85 will cling tighter to the leg, than the rest of the stocking which is more elastic, and will also force the inner top against the leg and the combined strength of the two tops prevent the movement of the muscles of the 90 leg from causing the stocking to work down and become loose, this effect is caused by this new combination which readily allows the weaker part of the stocking to give with the muscles of the leg, but the stronger top always pulling the weaker parts back into position on the leg.

The operation or action of this stocking is very simple, the stocking is simply pulled on the leg and the top 3 binding and causing the two tops to hug the leg tightly and allowing the weaker parts of the stocking to give or act with the muscles of the leg and thus the top 3 holds the rest of the stocking in its proper place or position.

What I desire to claim is:

1. An article of manufacture comprising a hose having a body portion and a cuff portion of a plurality of fabric plies, one of said plies at a plurality of adjacent points 110

thruout its length being of greater thickness and strength thereby offering increased resistance to expansion than the other portion of said cuff portion, the inside diameter of one of said plies being of greater diameter than the inside diameter of the other portion of said cuff portion.

2. An article of manufacture comprising a hose having a body portion and a cuff portion of a plurality of overlying fabric plies, the outer ply of said cuff portion at a plurality of points thruout its length being of greater thickness and strength than the other portion of said cuff portion, thereby offering increased resistance to expansion than said other cuff portion, the inside diameter of said outer ply being greater than the inside diam-

eter of the other portion of said cuff portion.

3. A method of making a hose having a body portion and a cuff portion of a plurality of plies, which consists in constructing the plies of said cuff portion each of a plurality of threads with the threads of one of said plies under greater tension than the threads of the other ply, and then introducing into the ply having the less tension a plurality of additional threads thruout the area thereof.

Signed at New York, in the county of New York and State of New York this 1st day of August, A. D. 1922.

DANIEL YOUNG.
